UNITED STATES PATENT OFFICE.

GEORGE WASHINGTON PICKIN, OF EAU CLAIRE, WISCONSIN, ASSIGNOR OF ONE-HALF TO WILLIAM A. KINNEAR, OF SAME PLACE.

INHALER.

SPECIFICATION forming part of Letters Patent No. 590,376, dated September 21, 1897.

Application filed March 10, 1896. Serial No. 582,647. (No model.)

To all whom it may concern:

Be it known that I, GEORGE WASHINGTON PICKIN, a citizen of the United States, residing at Eau Claire, in the county of Eau Claire 5 and State of Wisconsin, have invented a new and useful Inhaler, of which the following is a specification.

This invention relates to inhalers for use in treating diseases of the air-passages of the head, throat, and lungs.

The object of the present invention is to provide a novel and efficient construction of inhaler formed in such manner as to inclose both the mouth and nose of the patient, the same being held upon the head by means of an elastic band passing around the head or neck and fastened to the inhaler at each end. The said inhaler is provided with a separable attachment constituting a chamber in which 15 may be placed the desired medicine either in liquid or powder form, and the body of the inhaler is provided with separate and independent air-passages, one constituting the inhaling-passage, affording communication 20 between the medicine-chamber and the body of the inhaler, and the other forming the exhaling-passages through which the breath of the patient escapes without entering the medicine-chamber, a single flap-valve being 25 located between said passages for automatically opening and closing the same.

The invention consists in certain novel features and details of construction and arrangement of parts, as hereinafter fully described, 30 illustrated in the drawings, and finally pointed out in the claims hereto appended.

In the accompanying drawings, Figure 1 is a perspective view of the inhaler constructed in accordance with the present invention. 40 Fig. 2 is a longitudinal sectional view of the same. Fig. 3 is a reverse plan view of the same, showing the pivoted cut-off or regulator controlling the exhalation-passage. Fig. 4 is a detail perspective view of the flap-valve and its holder. Fig. 5 is a similar view of the removable perforate disk of the medicine-chamber. Fig. 6 is a sectional view of a modified form of medicine-chamber. Fig. 7 is an inside face view of one of the telescopic 45 sections thereof. Fig. 8 is a detail elevation 50

of the medicine-chamber, showing the air-ports and pivoted cover for covering the same.

Similar numerals of reference designate corresponding parts in the several figures of the drawings.

55

Referring to the accompanying drawings, 1 designates the body of the inhaler, which is of substantially conical form, as shown, the large end of the cone forming the mouth-and-nose-receiving portion of the inhaler. The 60 mouth 2 of the inhaler is of irregular form, being fashioned with especial reference to the facial anatomy, the upper portion of the inhaler being cut away in V shape, as indicated at 3, to accommodate the nose of the patient, 65 while the cheek portions 4, between the angle of the V and the lower portion of the mouth, are curved to fit snugly against the face upon either side of the nose, the lower portion 5 being given a gentle curve to accommodate 70 the same to the chin. This edge is turned over or rolled to afford sufficient thickness to make the same fit comfortably and closely against the face, and the same may, if desired, be covered with textile material or 75 padded, so that the contour of the mouth of the inhaler will conform closely and snugly to the face of the patient and effectively exclude air at such point.

The rear portion of the inhaler is cylindrical in form, as indicated at 6, and this is adapted to receive a medicine-chamber 7. This chamber is in the form of an annular case or cylinder, in the outer end of which is arranged a stationary perforated disk 7a. In 80 the inner end of the chamber or case 7 is removably inserted a second perforated disk 8, having a cross bar or wire 9, forming a handle by which the disk may be removed and replaced, and also provided with an annular 85 flange 10 for giving the proper support to the disk when in place and preventing the same from tilting and thus becoming loose. The disk 8 fits into the chamber 7 with sufficient tightness to cause the same to be retained 90 therein by frictional contact. Between the two perforated disks of the chamber 7 is placed a sponge or other absorbent 11, which will take up the medicine to be used, or the sponge may be removed and medicine placed 95 100

within the chamber in dry or powdered form. The medicine-chamber 7 is preferably applied to the inhaler proper by a frictional telescopic connection. Outside of and beyond 5 the disk 7^a is another disk 12, having air-ports 13 and also provided with a centrally-pivoted cover 14, which may be turned in such manner as to either open or close the air-ports. In use the air-ports are left open, 10 but when not in use the air-ports are closed to prevent the too-rapid evaporation of the medicine contained within the medicine-chamber.

In Figs. 6 and 7 I have illustrated a medicine-chamber which is particularly adapted 15 for holding medicine in liquid form. This comprises two telescopic cylindrical cases 15 and 16, the inner or forward one, 15, having a central aperture by which the air is admitted to the inhaler and also provided with an annular flange 17, adapted to embrace the cylindrical portion of the inhaler, whereby the said medicine case or chamber may be connected in the inhaler. The telescoping 20 portions of the case or medicine-chamber are provided in their peripheries or outer flanges with air-inlet openings 18, which may be brought into or thrown out of alignment by rotating one part of the case relatively to the 25 other. Within the inner member of this case or medicine-chamber is a spirally-coiled web 19 of the same width as the peripheral flange surrounding the same, the said web forming an involute air-passage, through which the air 30 passes to the central opening 17 and thence to the inhaler. A felt or textile packing-disk 20 is arranged in the outer end of the outer portion of the case or medicine-chamber, so as to prevent the air from getting by the edges of 35 the web 19, thus forcing the same to travel in said involute passage. A spirally-coiled wire is placed in this involute passage and extends from one end to the other thereof, the 40 said wire forming a base or support about or around which may be placed absorbent cotton or any other absorbent material which will take up medicine in liquid form and hold the same. By this construction and arrangement the air is forced to travel an extended 45 course before it reaches the inhaler, and being subjected throughout such course to the medicine the air becomes thoroughly impregnated with such medicine, thus adding to the 50 efficacy of the treatment.

Within the inhaler is permanently secured 55 an elbow-pipe 21, the lower end of which communicates, through an opening 22 in the lower part of the inhaler, with the outer atmosphere. This opening 22 is surrounded by an 60 annular flange 23. This opening is closed a little more than half by a stationary and substantially semicircular diaphragm having semicircular notches 24, and upon such diaphragm as a support is pivotally mounted a 65 rotatable cut-off 25 in the form of a substantially semicircular plate provided with semicircular notches in its diametrical edge which

correspond to the notches of the stationary diaphragm. The cut-off has a depending stud 27, by which it may be manipulated or 70 turned for regulating the size of the exhalation-passage.

Within the rear annular portion of the inhaler and between the rear end of the tubular elbow 21 and the medicine-chamber 6 is 75 located a flap-valve 28. This valve is pivoted at one edge to a removable valve-seat 29 in the form of a disk provided with an annular flange 30, entirely or partially surrounding the same and bearing snugly within the 80 cylindrical portion of the inhaler, thus serving to prevent the valve-seat from tilting. The valve-seat has a central opening 31, affording communication between the inhaler and the medicine-chamber, and such opening 85 is crossed by a diametrical bar or wire 32, forming a finger-hold by means of which the valve-seat and valve may be removed when necessary. The valve 28 works between the inhalation-passage 31 and the inner orifice of the 90 elbow-pipe 21, forming the exhalation-passage, and alternately closes one and opens the other during respiration, thus rendering the inhaler absolutely safe.

It will be apparent from the foregoing description that a very simple and efficient inhaler is produced, the advantage gained by its peculiar construction being that the remedies may be applied and used while the person is at rest, and even during sleep, thus 95 providing for a continuous application of the remedy throughout the night while the system is relaxed and in condition to more readily receive the full benefit thereof. The construction is such that it is impossible for the 100 air-passages to become closed and thereby exclude the necessary amount of air, the valve being so arranged that should one passage become obstructed air would be drawn through 105 the other passage, it being impossible for the 110 valve to simultaneously close both passages.

The inhaler may be worn by the patient while in any position, either lying on the back or side or reclining at an angle, and is particularly designed for use in treating diseases 115 of the air-passages of the head, throat, and lungs.

It will be apparent that changes in the form, proportion, and minor details of construction may be resorted to without departing from 120 the spirit or sacrificing any of the advantages of this invention.

Having thus described the invention, what is claimed as new is—

1. An inhaler provided with an exhalation-passage and having a medicine-chamber provided with an inhalation-passage leading therefrom to the interior of the inhaler, in combination with a valve located between the said passages and adapted to be operated 125 automatically by respiration to alternately close and open said passages, substantially as and for the purpose described.
2. An inhaler provided with an internally-

arranged tubular elbow forming the exhalation-passage, in combination with a medicine-chamber attached to the body of the inhaler, a valve-seat removably fitted in the inhaler 5 in front of the medicine-chamber, and a valve located between the exhalation-passage and an opening in the valve-seat forming the inhalation-passage, said valve being adapted to be operated automatically by respiration to alternately open and close said passages, substantially as described.

3. In an inhaler, a medicine-chamber of approximately cylindrical form provided with end pieces, and having a peripheral inlet, and

a central outlet in one of the end pieces, and 15 having a spiral passage communicating at its ends with, respectively, the said inlet and outlet, and a spiral support for an absorbent material located in the said spiral passage, substantially as described.

20 In testimony that I claim the foregoing as my own I have hereto affixed my signature in the presence of two witnesses.

GEORGE WASHINGTON PICKIN.

Witnesses:

ASA C. WOOD,
THOMAS HUTCHINSON.
